Attorney—Lyon & Lyon

ABSTRACT: A low-cost cartridge constructed from folded box board or the like for typewriter ribbon and similar articles. The cartridge permits handling of the ribbon and insertion into the machine without the operator's hands coming into contact with the ribbon. The unique manner in which the cartridge is folded from the box board permits it to secure the ribbon as well as the core inside the cartridge and this is accomplished with a single fastening means.

RIBBON CARTRIDGE

BACKGROUND OF THE INVENTION

A search of the prior art has developed the following patents:

Schloss et al.	1,154,212	Scott	2,327,156
Pratt	1,889,933	Koenig	2,824,641
Miller	1,927,667	Becker	2,890,821
Wonder	2,101,355	Monroe	3,000,494
Stone	2,555,456	Lasher et al.	3,381,810
Urso	3,294,228		

Prior art devices require either more than one separate piece of cardboard or the like or necessitate the interlocking or joining of various portions of the package forming members in order to secure the same in its enclosed position. Thus, all of these prior devices involve more costly stamping and folding procedures and the extra joining steps also contribute to additional costs.

SUMMARY OF THE INVENTION

The present invention comprises a single die-cut piece of flat material such as box board or a flexible plastic material. It is the particular pattern in which the board is cut and scored for folding that permits it to be folded into a cartridge by which a single fastener secures all of the folds and also provides a centering tongue for the spool enclosed within the cartridge.

It is an object, therefore, of the present invention to provide an improved construction for cartridges to contain carbon ribbon and the like for typewriters and similar machines.

More specifically, it is an object of the present invention to provide a low-cost disposable cartridge for typewriter ribbon which can be quickly loaded into the typewriter and prevents the typist's hands from coming into direct contact with the carbon ribbon itself.

It is a particular advantage of the present invention that the cartridge is made of one piece of cardboard or the like folded in such a manner as to enclose the spool of ribbon and to be securely fastened in such configuration with a single fastening element.

DESCRIPTION OF THE DRAWINGS

FIG. 1 is a plan view of the cartridge having a spool of ribbon enclosed therein.

FIG. 2 is a plan view of the cartridge as it is die cut and scored but unfolded.

FIG. 3 is a perspective view of the cartridge having a spool therein, with the cartridge partly folded.

FIG. 4 is a perspective view of the completed cartridge showing the opposite side from that shown in FIG. 3.

FIG. 5 is an enlarged sectional elevation taken along the line 5-5 of FIG. 1.

DESCRIPTION OF THE PREFERRED EMBODIMENT

FIG. 2 shows the cartridge blank after it is die cut of box board or other similar material. The heavy lines outlining the blank shown in FIG. 2 are the portions which are cut and the dotted lines indicated portions of the blank which are scored for folding purposes. It will be noted that a centering tongue 11 is cut within the body of the blank. The blank consists of a base portion 10 having a generally octagonal configuration with a centering tongue 11 cut therein. The base has attached thereto side flaps 12 and 14 which include side flap extensions 13 and 115. It will be noted that the end of the centering tongue 11 extends through the side flap extension portion 15. The blank also includes a tab flap 16 attached to the base through flap extension 17 and a semielliptical flap 18 attached to the base through extension 19. Each of the flaps 12, 14, 16 and 18 is provided with die cut apertures 12a, 14a, 16a and 18a respectively. The centering tongue 11 is likewise provided with aperture 11a.

The manner of folding and assembling the cartridge with a spool of ribbon is best demonstrated in FIG. 3 and FIG. 5. A ribbon spool 22 having ribbon 24 wound thereon is placed upon the base member 10 and the centering tongue 11 is extended upwardly through the center aperture 26. The centering tongue 11 is bent over the spool in the manner shown in FIG. 3 whereby the tongue forms a centering rib 27 to hold the spool 22 in place within the cartridge.

The side flap 14 is next folded downwardly over the centering tongue 11 and following that, side flap 12 is bent upwardly and over flap 14. Next, tab flap 16 is bent upwardly and over to lay on top of side flap 12, following which the cover flap 18 is likewise bent downwardly over the other flaps. The apertures 12a through 18a are all aligned with aperture 11a and a rivet 28 is extended therethrough and affixed securing all of the flaps in overlapping position as shown in FIG. 5.

The removal of the centering tongue 11 from the base member 10 provides an opening 30 so that a tensioning spring found in most machines can contact the ribbon directly to provide a slight drag to prevent freewheeling. In addition, it leaves an inspection slot 30 through the base portion 10 so that one may see the type, color, etc. of ribbon within the cartridge and can determine whether or not the cartridge is full. The tab flap 16 has a corner 20 which provides a finger tab for grasping the cartridge for insertion thereof into a typewriter or other similar machines. It will be obvious that the flap extensions 13, 15, 17 and 19 form the edges of the cartridge as shown in FIG. 4. The four spaces intermediate the extensions 13, 15, 17 and 19 as well as the aperture 29 provided in extension 15 by the removal of the centering tongue 11 all provide apertures through which the ribbon 23 can be fed so that regardless of the orientation of the cartridge within a machine the ribbon can be reeved through any of these apertures to feed in the required direction.

The cartridge is preferably constructed of cardboard or folded boxboard which is of low cost. However, it is contemplated that thin foldable plastic material could likewise be used. The intention is to construct a cartridge which is of sufficiently low cost as to be truly a disposable item. It is an advantage of the invention that the provision of the centering rib 27 prevents loose spools 22, or the carbon ribbon 24 itself from falling out of the cartridge. Carbon ribbon commonly used in typewriter and similar machines is extremely dirty if handled, since the carbon is quite easily rubbed off with the hands. Thus it is an important feature of the invention that the cartridge keep the installer's hands clean while permitting him to handle the cartridge through the use of the finger tab 20. It is also noted that the cartridge permits the leader of the ribbon to be fixed to the cartridge case so that the cartridge can be rapidly loaded into the typewriter and then the leader threaded in a desired manner.

While a preferred embodiment of the present invention has been shown and described, it will be obvious to persons skilled in the art that changes and modifications therein can be made without departing from the invention in its broader aspects; and it is the aim of the appended claims to cover all such changes, modifications, and equivalents as fall within the true scope and spirit of the invention.

I claim:

1. A cartridge constructed of foldable material and suitable for containing a spooled object, comprising:
a planar base portion having an octagonal shape;
four flaps attached to said base at positions about the edge thereof each spaced 90° from the next, said flaps folded over said base into an end overlapping relationship whereby said flaps are spaced parallel with respect to said base;
centering means attached to said base and extending upwardly therefrom, said centering means having means for fastening the same to said flaps.
2. The cartridge described in claim 1 wherein one of said flaps is provided with an enlarged corner portion providing a finger tab.

3. The device set forth in claim 1 wherein said centering means comprises a tongue portion cut from said base, said tongue being folded to provide a single centering rib extending away from said base near the center thereof and the remainder being folded into a spaced parallel relationship to said base. 5

4. The device set forth in claim 3 wherein said tongue portion is cut out of a portion of one of said side flaps as well as said base, said cut out from said side flap providing in the folded condition a feed aperture for spooled material stored in said cartridge.

5. The device set forth in claim 4 further including a spool having a center aperture, said centering rib extending through said aperture, said spool having a continuous strip of material thereon.

6. A cartridge constructed of foldable material and suitable for containing a spooled object, comprising:

a base portion having a planar octagonal shape,
a pair of side flaps each having a flap extension connected to opposed edges of said base portion, said flap extensions being folded upwardly from said base portion, said flaps being folded downwardly from said upwardly extending extensions and extending diametrically across said base portion in parallel spaced relationship, said side flaps having their ends overlapping near the center of said base;
a tab flap having a flap extension connected to an edge of said base portion 90° disposed from said side flaps, said flap extension being folded upwardly from said base, said

tab flap being folded downwardly from said extension and disposed across said base portion in parallel spaced relationship overlapping said other flaps;
a cover flap having a flap extension connected to the edge of said base portion opposite said tab flap, said flap extension being folded upwardly from said base, said cover flap being folded downwardly from said extension and disposed across said base in parallel spaced relationship overlapping said other flaps;

10 a centering tongue having a centering rib attached to the center of said base portion and extending upwardly therefrom, said tongue being folded downwardly from said rib and disposed in parallel spaced relationship to said base and overlapping said other flaps; and
fastening means securing all said flaps and said tongue together at a point where they are mutually overlapping.

7. The article described in claim 6 wherein said tab flap has two exterior corners one of which is extended to provide a finger tab, the other corner being rounded in general conformity with the shape of said spooled material; said cover flap having two exterior corners both of which are rounded in conformity with the shape of said spooled material.

part of The article described in claim 7 wherein said centering tongue is cut from said base portion and from a part of one 25 of said side flap extensions to provide an open slot in said base and an aperture in said side flap extension.
